SIZING TUBE

Palmer G. Hendrix, Hickory, N. C., assignor to
 Hickory Specialty Company, Hickory, N. C., a
 corporation of New Jersey

Application March 25, 1949, Serial No. 83,323

9 Claims. (Cl. 242—110)

1

This invention relates to an improved winding or sizing tube for synthetic yarns, such as nylon and Vinyon, and onto which the synthetic yarn is wound after having been treated with a sizing emulsion.

Sizing emulsion is usually applied to synthetic yarns, such as nylon, as it is wound from pirns, bobbins or the like, onto a sizing tube which is usually of plastic material and is about six inches in diameter and seven inches long. The yarn is usually wound onto the sizing tube on a winding machine such as a Foster winder, and such as is shown in the patent to J. O. McKean Number 1,647,534 of November 1, 1927. As the yarn passes from the pirn to the sizing tube, it passes over a rotating emulsion roller which is partially submerged in a sizing emulsion carried by a reservoir supported on one side of the machine. The sizing tube is mounted on a rotating spindle on which the tube is usually held by expanded continuous coiled springs bearing against the internal wall of the sizing tube. Now, in order to remove the sizing tube from the spindle, the continuous coiled springs are allowed to contract slightly to thereby permit the operator to slide the sizing tube off the spindle.

After the yarn has been subjected to the sizing emulsion and has been wound onto the sizing tube, the sizing tube is then placed in an oven where it is subjected to elevated temperatures at relatively high humidity to thereby allow a limited amount of shrinkage or contraction of the yarn on the sizing tube.

It is an object of this invention to provide a sizing tube which is designed to retain its diameter during the winding operation while applying sizing emulsion to the yarn and to provide means for allowing the tube to collapse or contract a predetermined amount, thereby decreasing its diameter, while the yarn wound thereon shrinks or contracts a predetermined amount, to thus increase the elasticity of the nylon yarn as well as to provide a uniform amount of elasticity in the synthetic yarn wound on a particular tube.

It is another object of this invention to provide a sizing tube of the type described having a slot of predetermined width extending throughout the length of the tube and to provide locking means at each end of the slot connected to the tube to normally prevent the slot from closing when under tension of the synthetic yarn being wound thereon during a winding and sizing operation. After the tube with the treated yarn thereon is removed from the winding machine, the locking means at the ends of the slot may be released and the slot in the tube may be per-

2

mitted to decrease in width as the yarn contracts on the tube.

Other means are provided to prevent the opposite walls of the slot from engaging each other upon the yarn contracting on the tube to thereby not only cause a predetermined amount of contraction of the yarn to take place, but also preventing the yarn from being pinched between the walls of the slot in the tube.

10 Some of the objects of the invention having been stated, other objects will appear as the description proceeds when taken in connection with the accompanying drawings, in which

Figure 1 is an isometric view of the improved sizing tube showing the locking means holding the walls of the longitudinal slot apart from each other;

Figure 2 is an enlarged vertical sectional view taken along the line 2—2 in Figure 1;

20 Figure 3 is an enlarged sectional plan view taken along the line 3—3 in Figure 1;

Figure 4 is a transverse sectional view taken along the line 4—4 in Figure 1 and showing some of the nylon yarn wound thereon with part of the yarn being broken away for purposes of clarity;

Figure 5 is an elevation of the sizing tube with the nylon yarn wound thereon and showing the locking means released and in the position it will assume when the yarn has contracted to about one half of its limit;

Figure 6 is an enlarged elevation of the upper central portions of Figures 1 and 4 and showing the locking means in the position it will assume when the yarn on the tube will have contracted to its limit;

Figure 7 is an elevation of another form of the sizing tube with a modified form of locking and guiding means applied thereto;

40 Figure 8 is an enlarged transverse sectional view taken substantially along the line 8—8 in Figure 7;

Figure 9 is an enlarged plan view taken substantially along the line 9—9 in Figure 7 and showing a detail of the modified locking means;

45 Figure 10 is an enlarged elevation looking at the inner side of the tube at the upper portion of Figure 7 and also being taken substantially along the line 10—10 in Figure 9;

50 Figure 11 is another form of the invention wherein the modified form of guiding means, heretofore referred to, is employed along with a hinged spacer for closing the slot and preventing contraction of the tube during the winding operation;

55 Figure 12 is an enlarged transverse sectional

3

view taken substantially along the line 12—12 in Figure 11;

Figure 13 is a sectional view similar to Figure 12 but showing the closing member or spacer swung inwardly;

Figure 14 is a top plan view of the tube shown in Figure 1;

Figure 15 is an enlarged elevation looking at the inside of the tube and at the opposite side from that shown in Figure 11 and is taken substantially along the line 15—15 in Figure 14.

Referring more specifically to the drawings, the numeral 10 indicates a sizing tube which may be of any desired material, such as laminated plastic, molded plastic, wood, or any other contractable material. The tube 10 has a slot of predetermined width extending throughout the length of the tube. The slot is defined by walls 12 and 13 which are representative of the width of the slot and their distance apart may be varied according to the percentage of elasticity desired in the sized yarn.

A locking member 15 is pivotally connected as by a pin 16 to the tubular member 10 adjacent the wall 12 at the upper end of the slot 11. A similar locking member 15' is mounted at the other end of the slot 11, and since the locking members 15 and 15' are identical, the parts associated with the locking member 15' will bear the same reference characters as like parts associated with the locking member 15, with the prime notation added.

The locking member 15 is preferably U-shaped in cross section and its left-hand portion in Figure 1 is adapted to slidably engage the upper edge of the tubular member 10. It will be noted in Figure 4 that the locking member 15 is also curved to conform, generally, to the curvature of the inner and outer walls of the tube 10. Thus, the member 15 not only serves as a locking means but also serves as a guide member to insure that the walls 12 and 13 are properly aligned as they move toward each other with contraction of the tube 10 as will be later described.

A pin 20 is fixedly mounted in the locking member 15, as by a pressed fit, and spans the distance between the flange or leg portions of the U-shaped member 15.

The flanges of the U-shaped member 15 are provided with a plurality of spaced sets of alined bores 19 which are adapted to snugly receive a second pin 21, similar to pin 20. The pin 21 may be inserted in any one of the sets of alined bores 19 in the member 15 according to the amount that it is desired the yarn shall contract on the tube 10. It will be noted that the bores 19 are positioned inwardly relative to the pivot pin 16 toward the opposite end of the tubular member 10 so as to position the pin 21 inwardly when inserted in the bores 19, for purposes to be later described. The locking member 15 has a cut away portion 23 at its right-hand end in Figure 1 to thus permit the locking member 15 to be moved in a clockwise direction in Figure 1 to the position shown in Figure 5.

As the yarn is passed through a sizing emulsion and during a winding operation, the synthetic yarn, indicated at 25 in Figures 4 and 5, is wound on the tubular member 10 with the locking members 15 and 15' in the position shown in Figure 1, as a result of which the wall 13 of the slot 11 will bear against the pin 20 and the pivot pin 16 will prevent the walls 12 and 13 from moving towards each other during the

4

winding operation, to prevent the tube from being contracted on the spindle from which it would then be immovable.

The tubular member 10 is then removed from the spindle of the winding machine and the locking members 15 and 15' are moved outwardly so as to move the pins 20 and 20' out of engagement with the wall 13 of the slot 11, or to the position shown in Figure 5. The tube is then placed in an oven for approximately 30 minutes with a wet bulb temperature of approximately 170° F. and a dry bulb temperature of approximately 160° F. The yarn then contracts and causes the tubular member 10 to contract as shown in Figure 5 and finally as shown in Figure 6.

The tubular member 10 is provided with notches 26 and 26' at opposite ends thereof which are spaced a predetermined distance from the wall 13 of the slot 11, and it is thus seen in Figure 6 that contraction or shrinkage of the yarn will cause the wall 13 to move into engagement with the pin 21 which is preferably spaced slightly apart from the wall 12. Since the pin 21 is positioned inwardly of the pivot pin 16, the wall 13 will act as a cam on the pin 21 to thus move the lock member 15 in a counterclockwise direction from the position shown in Figure 5 to that shown in Figure 6 to thus cause the pin 20 to move into engagement with the notch 26 and to thereby move the lock member 15 to a position parallel with the end of the tubular member 10.

It is manifest that the left-hand or free end of the lock member 15 in Figure 1 must move toward the center of the tubular member 10, as the diameter of the tubular member decreases during the contraction of the nylon yarns on the tubular member 10. Therefore, the tubular member 10 is provided with notches 27 and 27' the inner surfaces of which extend at an angle relative to a line tangent to the periphery of the tubular member and these notches are disposed adjacent the outer wall of the U-shaped members 15 and 15' and it will be noted in Figure 3 that the pivot pin 16 loosely penetrates the wall of the tubular member 10 so as to permit the member 15 to move inwardly at its free end as the diameter of the tubular member 10 decreases.

It will be noted in Figure 6 that the pin 21 not only serves to move the locking member 15 inwardly at its left-hand end, but also serves as a stop member to prevent the wall 13 from moving into engagement with the wall 12 of the slot 11 during contraction of the yarn to thus prevent the yarn from being pinched between the walls 12 and 13.

If the walls 12 and 13 were permitted to engage each other, the yarn would not only be damaged, but would also adhere to the tubular member 10 adjacent the opening 11 and this would interfere with the removal of the yarn 25 from the tubular member 10.

It might be stated that the notch 26 in the tubular member 10 is not provided as a means of locking the tubular member 10 in a contracted position, but is merely provided to permit the member 15 to be moved to a position parallel to the end of the tubular member 10 to thus permit the tubular member 10 to be placed on end for storage purposes.

Modified locking means

Referring to Figures 7, 8, 9 and 10, there is

shown a modified form of the invention comprising a winding or sizing tube 40 which is identical to the tube 10 in the original form of the invention. The tube 40 also has a slot 41 of predetermined width extending throughout the length of the tube 40. The slot is defined by walls 42 and 43 and, as in the original form of the invention, these walls are representative of the width of the slot and their distance apart may be varied according to the percentage of elasticity desired in the yarn to be wound thereon.

A curved guide member 45 is pivotally connected as by a pin 46 to the tubular member 40 adjacent the wall 42 at the upper end of the slot 41. A curved guide member 45', which is identical to the guide member 45 but is the reverse of the guide member 45, is mounted at the lower end of the slot 41. The parts associated with the guide member 45' will bear the same reference characters as like parts associated with the guide member 45 with the prime notation added.

The guide member 45 is preferably U-shaped in cross section and thus has outer and inner flange portions 44 and 47 integral therewith which are adapted to engage the outer and inner walls of the tubular member 40 to thus serve as a guiding means as the walls of the slot 41 moves towards each other during contraction of the yarn, as the locking member 15 does in the original form of the invention.

Since the free end of the guide member 45 must move towards the center of the tubular member 40 upon contraction of the tube, the tubular member 40 is also provided with a cavity 51 in its periphery adjacent the pivot pin 46, the bottom of which extends at an angle relative to a line tangent to the periphery of the tubular member. It will be noted in Figure 9 that the pivot pin 46 also loosely penetrates the wall of the tubular member 40 so as to permit the member 45 to move inwardly at its free end as the diameter of the tubular member 40 decreases.

Secured, as by a pressed fit, in the guide member 45 and spanning the distance between its flanges 44 and 47 is a transverse pin 54 which is positioned inwardly relative to the pivot pin 46 toward the opposite end of the tubular member 40 and is spaced slightly apart from the wall 42 of the slot 41 for the same reason that the pin 21 is so positioned in the guide member 15 in the original form of the invention.

The curved locking member 45 also has a cut away portion 55 at its right-hand end in Figures 7 and 9 to permit the guide member 45 to be swung outwardly if desired. However, it is to be noted that in the modified form of the invention it is not necessary that the guide members 45 and 45' be swung outwardly inasmuch as they do not have a pin adjacent their opposite ends engaging the wall 43 remote from their pivot points 46 and 46'. In fact, if so desired, there may be more than one pin similar to the pin 46 connecting the member 45 to the tubular member 40 adjacent the wall 42 of the slot 41 to thus prevent the member 45 from being swung outwardly. However, in the instance of more than one pin being used to secure the member 45 to the wall of the tubular member 40, any other pin similar to the pin 46 must loosely penetrate the wall of the member 40 to permit the free end of member 45 to move inwardly upon contraction of the tubular member 40.

Referring to Figures 8 and 9 it may be observed that the walls 42 and 43 of slot 41 are beveled so that the slot 41 is narrower at the outer surface

of the tubular member 40 than it is at the inner surface of the tubular member 40 and a spacing member 60 whose opposite edges are beveled to conform to the beveled walls 42 and 43 is adapted to be placed in the slot 41 formed by the walls 42 and 43. It will be noted in Figures 7 and 10 that opposite ends of the spacer 60 are notched as at 61 and 61' and the inner flange 48 of the guide member 45 in Figure 10 is cut away as at 62 to permit the narrower upper end of the spacer 60 formed by the notch 61 to engage the inner walls of the outer flange 47 of the guide member 45 when the spacer 60 is inserted in the slot 41. Obviously, the walls 42 and 43 are beveled to provide for ease of removal of the spacer 60 from the slot 41.

Since the spacer 60 engages the inner surfaces of the outer flanges 47 and 47' of the guide members 45 and 45', respectively, it is thus seen that the members 45 and 45' prevent the spacer 60 from being moved entirely through the slot 41 in the event that the walls 42 and 43 are spaced abnormally far apart and to also insure that the outer surface of the member 60 will be flush with the outer periphery of the tubular member 40. The function of the spacer 60 in the slot 41 is very similar to the function of the pin 29 in the locking member 15 in the original form of the invention, in that it prevents the walls 42 and 43 from being moved towards each other by contraction of the tubular member 40 as the yarn is being wound thereon. Since the spacer 60 extends for the full length of the slot 41, the spacer 60 also insures that the central portion of the tubular member 40 will not be contracted thus moving the central portions of the walls 42 and 43 towards each other although their outer ends may be locked, as may be the case in the original form of the invention.

After the yarn has been wound on the tube 40 the tubular member 40 is then removed from the spindle of the winding machine and the spacer 60 is moved inwardly toward the center or axis of the tubular member 40 and thus is removed from the slot 41. This will, of course, permit the yarn wound on the tubular member 40 to contract, as in the original form of the invention, until the wall 43 of the slot 41 moves into engagement with the pins 54 and 54' on the guide members 45 and 45', respectively, thus permitting a predetermined amount of contraction of the nylon yarns wound thereon.

Referring to Figures 11, 12, 13, 14 and 15, there may be observed still another modified form of the invention which is very similar to the modified form shown in Figures 7, 8, 9 and 10 and since all of the parts shown in Figures 11 to 15, inclusive, with the exception of the closing means for the slot in the tubular member, are identical to the parts shown in Figures 7 to 10, inclusive, a further description of these parts will not be given and like parts in Figures 11 to 14, inclusive, shall bear the same reference characters as the parts shown in Figures 7 to 10, inclusive.

In the form of the invention shown in Figures 11 to 15, inclusive, the spacer or closing means for the slot 41 is indicated at 60-a and is identical to the spacer 60 shown in Figures 7 to 10, inclusive, with the exception that this spacer 60-a has a hinge member 65 secured thereto as by screws 66 and this hinge member 65 is also secured to the inner wall of the tubular member 40 as by screws 67 adjacent the wall 43 of the slot 41. Opposite side edges of the spacer 60-a are beveled to conform to the bevelled walls 42 and

43 of the slot 41 as is the case with the spacer 60 shown in Figures 7 to 10, inclusive. Referring to Figures 11, 12, 14 and 15, it may be observed how the spacer 60—a may be swung into position to close the slot 41 and, in so doing, the member 60—a may bear against the inner surfaces of the outer flanges 47 and 47' of the guide members 45 and 45', respectively, thus insuring that the spacer 60—a will be flush at its outer surface with the outer periphery of the tubular member 40.

When the tubular member 40, as shown in Figures 11 to 15, inclusive, is removed from the spindle on which it is mounted during the winding operation, the spacer 60—a may then be 15 swung inwardly as shown in Figure 13 to thus permit the walls 42 and 43 of the slot 41 to move towards each other under contraction of the yarn wound on the tubular member 40 until the wall 43 engages the transverse pins 54 and 54' in the 20 guide members 45 and 45'. The hinging means for the spacer 60—a shown in Figures 11 to 15, inclusive, is shown as being a piano type hinge, however, this is shown by way of illustration only, inasmuch as the spacer 60—a may be hinged to the side wall 43 of the slot 41 in any desired manner.

Tests have shown that nylon yarns which have been sized on tubes not having the slot therein, such as in the present invention, usually will break when stretched to twelve and one-half percent elasticity, while, for example, with an opening of a width of one inch in a tube having a circumference of eighteen inches, it has been found that the elasticity of the yarn will be increased an additional five percent or a total of seventeen and one-half percent. Tests have shown that an additional fourteen percent elasticity is possible with the present invention and in which instance the width of the slot 11 would be increased to two and one-half inches.

It is obvious that by increasing the elasticity in the yarn in the manner heretofore described not only the uniformity of elasticity in the yarn is improved, which would result in straighter seams in full fashioned hosiery than have heretofore been possible, but this also reduces the snagging and pull threads in hosiery manufacturing processes as well as greatly increasing the useful life of the hosiery inasmuch as the increased elasticity would alleviate the possible occurrence of runs in the hose, particularly in pulling the hose over one's foot.

In the weaving of fabrics in which nylon warp or filling yarns are used, yarns are usually not subjected to a sizing emulsion. However, when nylon yarns are woven into cloth, unevenness of elasticity of the nylon yarns has often resulted in a fabric of uneven or irregular appearance caused by stripes extending transversely or in the picks of the fabric and which are generally referred to as bearing and tier marks. These marks have usually been the result of uneven density in the nylon yarns which has caused a slub-like effect in the yarn.

In order to produce a fabric which does not have the bearing or tier marks hereinbefore referred to, the nylon yarn is wound on the tube 10 in the manner heretofore described with the exception that the yarn is not necessarily passed through a sizing emulsion. However, the yarn on the tube 10 is then processed in the manner heretofore described to thus shrink or contract the yarn a predetermined amount to thus produce

an even texture and an even elasticity in the yarn throughout its entire length.

The present invention is also useful in the preparation of nylon sewing threads, such as is used in the seaming of nylon hosiery. Heretofore, nylon sewing threads have usually been placed in skeins and then the skeins with the nylon yarns therein have been placed in hot or boiling water for a predetermined period and then dried and wound on spools after which the yarn has been twisted. It is manifest that the present invention will greatly reduce the cost of preparation of nylon sewing threads inasmuch as the yarn may be wound from the pirns, on which it is usually wound when received in the processing plant, onto the tube 10 in the manner heretofore described. The tube 10 is removed from the winding machine and may be placed in an oven in the same manner as heretofore described for other synthetic yarns with the nylon sewing thread wound thereon and with the locking members 15 and 15' moved outwardly to the position shown in Figure 5 to thus permit the yarn to shrink a predetermined amount. The yarn may then be dried while it is still on the tubular member 10 and may be unwound on the twisting frame while still on the tube 10 or it may be wound from tube 10 onto suitable spools for placing on a twister frame. This eliminates the skeins as well as the necessity of subjecting the sewing thread to hot or boiling water. This latter process also provides a better sewing thread than has heretofore been possible inasmuch as the sewing thread, when placed in the skeins, quite often becomes entangled with other packages or bunches of nylon yarns, thus resulting in the yarn becoming severed in various places along its length and also interfering with a possible uniformity of elasticity throughout its length.

The present method of treating synthetic yarns used in manufacturing full fashioned hosiery contracts the yarn in such a manner that the over-all lengths of seamed hosiery may be uniform prior to and after subjecting the hose, while on forms, to a heat treatment so as to set the hose to hold its shape. This operation is usually referred to as pre-boarding. Heretofore, uneven elasticity in the yarn used in hosiery has caused the hose to vary up to two inches in length after pre-boarding while all the hose in a particular group may have been exactly the same length prior to pre-boarding.

In the drawings and specification there has been set forth a preferred embodiment of the invention, and although specific terms are employed, they are used in a generic and descriptive sense only, and not for purposes of limitation, the scope of the invention being defined in the claims.

I claim:

1. Yarn holding means comprising a tube onto which yarn is adapted to be wound and having a slot extending longitudinally thereof for the entire length of the tube, means for holding the walls of said slot in spaced relation to each other, said means being movable to another position to allow movement of the walls of said slot toward each other upon contraction of the yarn disposed on said tube, said tube also being provided with other means for limiting movement of the walls of said slot toward each other after the first-named means has been adapted to allow movement of the edges of said opening toward each other.
2. A sizing tube adapted to have synthetic

yarns saturated with a sizing emulsion wound thereon, said sizing tube having a slot extending throughout the length of the tube, locking means pivotally connected to the sizing tube adjacent one side of the slot and spanning the slot and having stop means for normally preventing the walls of said slot from moving toward each other under contraction of the synthetic yarns as they are wound thereon, the locking means being movable out of locking position to thereby permit the walls of the slot to move toward each other after the yarn has been wound on the tube and due to contraction of the yarn, said tube having a cavity in its outer surface adjacent the pivoted end of the locking means, the bottom of said cavity extending at an angle relative to a line tangent to the periphery of the tube, whereby, upon the stop means being moved from between said walls, the locking means may move inwardly at its free end toward the axis of the tube during contraction of the tube.

3. A tubular member adapted to have synthetic yarns wound thereon, said tubular member having a slot extending throughout the length of the tubular member, a locking member substantially U-shaped in cross-section adapted to be mounted on opposite ends of the tubular member and to span the width of said slot, each of said U-shaped locking members having means for preventing the walls of the slot from moving towards each other during the winding of synthetic yarn thereon, the locking members being movable to another position to thus permit the walls of the slot in the tubular member to move toward each other during shrinkage of the yarn carried thereby to thus increase the elastic limits of the yarn.

4. A winding tube adapted to have synthetic yarns wound thereon, said winding tube having a slot extending throughout the length of the tube, guide members spanning the ends of said slot and being connected to the tube adjacent one of the walls of said slot, a spacer member adapted to be inserted in said slot and extending substantially from one end thereof to the other and means on the guide members for supporting the opposite ends of the said spacer and to prevent said spacer from projecting beyond the outer periphery of the tube whereby the spacer may be inserted in the slot during a winding operation to prevent contraction of the tube and whereby the spacer may be removed from the said slot following the winding operation to permit contraction of the tube, the said guide members serving to insure that the walls of the slot shall remain in alignment with each other during contraction of the tube.

5. A winding tube adapted to have synthetic yarns wound thereon, said winding tube having a slot extending throughout the length of the tube, guide members adapted to close opposite ends of said slot, said guide members being substantially U-shaped in cross section and being secured at one end to the tube adjacent one of the walls of said slot, the other end of the guide member being adapted to slidably engage the tube adjacent the other wall of the slot, the inner flanges of said guide members being partially cut away, a spacer of substantially the same length as the tube and being hingedly connected to one of the walls of said slot and also being adapted to swing inwardly, the free edge of said spacer being adapted to engage the other wall of said slot, the opposite ends of said spacer also being adapted to engage the inner surfaces of the outer flanges of the guide members to thus pre-

vent the spacer from projecting beyond the outer periphery of the tube during a winding operation and whereby the spacer may be swung inwardly following the winding operation to thereby permit the walls of the slot to move towards each other due to contraction of the yarn.

6. A winding tube adapted to have synthetic yarns wound thereon, said winding tube having a slot extending throughout the length of the tube, guide members adapted to close opposite ends of said slot, said guide members being substantially U-shaped in cross section and being secured at one end to the tube adjacent one of the walls of said slot, the other end of the guide member being adapted to slidably engage the tube adjacent the other wall of the slot, the inner flanges of said guide members being partially cut away, a spacer of substantially the same length as the tube and being hingedly connected to one of the walls of said slot and also being adapted to swing inwardly, the free edge of said spacer being adapted to engage the other wall of said slot, the opposite ends of said spacer also being adapted to engage the inner surfaces of the outer flanges of the guide members to thus prevent the spacer from projecting beyond the outer periphery of the tube during a winding operation and whereby the spacer may be swung inwardly following the winding operation to thereby permit the walls of the slot to move towards each other due to contraction of the yarn, each of said guide members having a transverse pin therein adapted to be engaged by the wall of the slot remote from the end of the guide members secured to the tube to thereby restrict movement of the walls of the slot towards each other to allow a predetermined amount of contraction of the yarn on a particular tube according to the amount of electricity desired in the yarn.

7. A tubular member onto which yarn is adapted to be wound, said tubular member having a slot in its wall extending throughout the length of the periphery of the tubular member, means preventing contraction of the tubular member during a winding operation, said means being movable to allow the tension of the yarn thereon to contract the tubular member.

8. A sizing tube adapted to have synthetic yarns wound thereon, said sizing tube having a slot extending throughout the length of the periphery of the tube, locking means pivotally connected to the sizing tube adjacent one side of the slot and spanning the slot and having stop means for normally preventing the walls of said slot from moving toward each other under contraction of the synthetic yarns as they are wound thereon, the locking means being movable out of locking position to thereby permit the walls of the slot to move toward each other after the yarn has been wound on the tube and due to contraction of the yarn, said tube having a cavity in its outer surface adjacent the pivoted end of the locking means, the bottom of said cavity extending at an angle relative to a line tangent to the periphery of the tube, whereby, upon the stop means being moved from between said walls, the locking means may move inwardly at its free end toward the axis of the tube during contraction of the tube.

9. A tubular member adapted to have synthetic yarns saturated with sizing solution, wound thereon, said tubular member having a slot extending throughout the length of the periphery of the tubular member, locking members substantially U-shaped in cross-section adapted to be mounted

11

one on each end of the tubular member and to span the width of said slot, each of said U-shaped locking members having means for preventing the walls of the slot from moving towards each other during the winding of synthetic yarn thereon, the locking members being movable to another position to thus permit the walls of the slot in the tubular member to move toward each other during shrinkage of the yarn carried thereby to thus increase the elastic limits of the yarn.
